UNITED STATES PATENT OFFICE.

GOTTLIEB SCHNEIDER, OF BLUFFTON, INDIANA.

LUBRICATOR.

SPECIFICATION forming part of Letters Patent No. 755,802, dated March 29, 1904.

Application filed July 20, 1903. Serial No. 166,344. (No model.)

To all whom it may concern:

Be it known that I, GOTTLIEB SCHNEIDER, a citizen of the United States, residing at Bluffton, in the county of Wells and State of Indiana, have invented a new and useful Lubricator, of which the following is a specification.

This invention relates to lubricators, and more especially to lubricators for windmills, in which it is desirable that the lubricator may 10 be so constructed that it may be supported at the top of the windmill-tower and operated at intervals by a person on the ground at the base of the tower.

The principal object of the invention is to 15 provide in a lubricator for the purpose specified means for discharging from the reservoir of the lubricator a predetermined quantity of oil and means for distributing the oil so discharged to the different portions of the wind- 20 mill-gearing in quantities proportionate to the requirements for oil at the different points to which it is distributed.

A further object of the invention is to provide in a lubricator of the type specified an 25 improved form of measuring discharge-valve by means of which the waste of the oil from feeding excessive quantities to the bearings of the windmill-gearing may be effectively prevented and which will at all times be ready 30 for positive and efficient action.

With the objects above mentioned and others in view, which will appear as the invention is more fully disclosed, the same consists in the construction and combination of 35 parts of a lubricator for windmills, as hereinafter described and claimed, and illustrated in the accompanying drawings, in which is illustrated a preferred form of embodiment of the invention capable of carrying the same 40 into practical operation, it being understood, however, that various changes in the form, proportions, and exact mode of assemblage of the elements therein exhibited may be made without departing from the spirit of the in- 45 vention.

In the drawings, Figure 1 is a view in vertical section through the lubricator. Fig. 2 is a detail view in section through the discharge-valve in a vertical plane at right 50 angles to the plane of section upon which Fig.

1 is taken. Fig. 3 is a detail view showing the stop devices to limit the range of movement of the rotatable valve-plug.

Corresponding parts are designated by the same characters of reference throughout. 55

Referring to the drawings in detail, 1 designates the side wall of the reservoir of the lubricator, which is preferably of cylindrical form and which may be constructed of any suitable material—such, for example, as gal- 60 vanized sheet-iron.

2 designates the cover of the reservoir, which is preferably of the form shown and which is adapted, while forming a sufficiently close fit within the top of the reservoir, to protect the 65 oil therein from contamination by foreign matter and to prevent evaporation, to be readily removed.

The bottom 3 of the reservoir is of heavier material than the sides and cover and is made 70 with a slight slope toward the center, at which is provided the discharge-opening 4, which is internally threaded for engagement with the threaded upper end 5 of a branch pipe extending up from the measuring discharge-valve 6. 75

The discharge-valve 6 comprises a tapered seat 7 of frusto-conical form, which communicates with the branch pipe 5 above mentioned by means of an oblong opening 8 and which is provided on the under side with a 80 large round opening communicating with the bore of a downwardly-disposed branch pipe 9. The valve-plug 10 is of frusto-conical form to insure smooth fitting within the tapered seat 7 and is formed with an internal cavity 11, 85 which has an inlet-opening 12 and a discharge-opening 13, separated by an interval of ninety degrees, the discharge-opening being closed when the inlet-opening registers with the oblong opening 8 in the upper part of the valve-seat and the inlet-opening being closed when the discharge-opening is over the open end of the lower branch pipe 9. The movement of the plug 10 within the valve-seat 7 is limited by a lug 14 upon the stem of the plug and a pair 90 of lugs 15 and 16, arranged upon the end of the valve-seat in position to be engaged by the lug 14. The plug 10 is secured in the seat by means of a washer 17, fitted over a reduced extension 18 upon the smaller end of the valve- 95

100

plug and secured upon the extension to rotate therewith. A nut 19 external to the washer holds it in position upon the extension 18.

Movement is imparted to the valve-plug by means of a lever-arm 20, secured upon the square end of the stem of the plug and provided near one end with an adjustable weight 21, secured in position upon the lever by means of a set-screw and provided at the other end with an opening 22, through which passes a wire 23, which extends from the lubricator downward to a point within reach by a person standing on the ground.

The lower branch pipe 9 is internally threaded for engagement with the threaded upper end of the distributing-pipe 24, which extends downward a suitable distance and is provided at its lower end with a nut 25, having the lower portion thereof rounded and externally threaded, as shown, for the engagement of a distributor 26, the bottom of which is formed into a cone 27, which projects upward within the chamber formed in the distributor and forms means to spread the oil outward toward the wall of the distributing-chamber. Along the line of junction of the bottom of the distributing-chamber with the side wall thereof there are formed a plurality of threaded apertures to receive distributor-pipes 28, which distribute the oil from the chamber to the various parts of the windmill-gearing at which the oil is required. These pipes 28 are adjusted in position in the threaded apertures in the bottom of the distributor, so that the ends of the pipes project above the bottom of the distributor-chamber to slightly different heights, the object of this arrangement being to insure the distribution of the oil through the pipes 28 in the proportions required by the different parts of the windmill-gearing. The quantity of oil discharged from the hollow valve-plug into the distributing-chamber at each movement of the valve-plug being fixed, the arrangement of the pipes 28 in the manner above specified will insure the passage of the greater portion of the oil through those pipes which have the shortest projections above the bottom of the distributing-chamber, and small quantities will pass out through the pipes which project above the bottom of the distributing-chamber to a greater height. The lubricator, as above described, will be supported in suitable position by any convenient form of supporting means, which forms no part of this invention, and therefore needs no description or illustration.

The lubricator is especially designed, as already mentioned, for use in lubricating the working parts of a windmill-gearing; but it is to be understood that the lubricator may also be used to advantage upon any form of machinery in which it is desirable to use a single oil-reservoir and a plurality of pipes fed by gravity to convey the oil from the reservoir to the point where it is required.

In use the reservoir of the lubricator will be filled with oil, and the cavity in the valve-plug 10 will also be filled at the same time, because the weight on the lever 20 keeps the valve-plug normally in such position that the inlet-opening 12 registers with the oblong opening 8 in the upper part of the tapered valve-seat, so that oil may flow freely from the reservoir into the cavity in the interior of the valve-plug 10. When it is desired to distribute oil from the reservoir to the bearings in the windmill-gearing or other machinery upon which the lubricator is employed, a pull upon the wire 23 will oscillate the lever 20 and turn the valve-plug sufficiently to bring the discharge-opening 13 over the bore on the lower branch pipe 9, so that the oil contained within the valve-plug may flow downward into the distributing-chamber and pass outward through the pipes 28 extending downward therefrom.

It will be readily understood from the foregoing description and the accompanying drawings that by varying the positions of the pipes 28 as regards the heights of their upper ends above the bottom of the distributing-chamber the quantity of oil passing through each of said pipes may be gradually adjusted to the requirements of each of the bearings and an economical distribution of the oil effected.

Having thus described the construction and operation of my invention, what I claim as new, and desire to secure by Letters Patent, is—

1. In a lubricator, a reservoir, a measuring discharge-valve, a distributing-chamber and distributing-pipes extending downward from the bottom of said chamber and having their upper ends projecting above the bottom of said distributing-chamber to distances proportionate to the quantities of oil desired to pass through the several pipes.

2. In a lubricator, a reservoir, a measuring discharge-valve, a distributing-chamber and distributing-pipes adjustably secured in the bottom of said distributing-chamber so that their upper ends may project above the bottom of said distributing-chamber.

3. In a lubricator, a reservoir, a measuring discharge-valve, a distributing-chamber having a conical bottom and distributing-pipes extending outward and downward from the bottom of said chamber and having their upper ends projecting above the bottom of said distributing-chamber at the side wall thereof to distances proportionate to the quantities of oil desired to be distributed through the several pipes.

4. In a lubricator, the combination with a reservoir of a distributing-chamber, means for supplying lubricating material to said distributing-chamber in predetermined quantities, and distributing-pipes having their upper ends projecting unequally above the floor of said chamber.

5. In a lubricator, the combination with a

reservoir of a distributing-chamber, a supply-pipe connecting said reservoir and distributing-chamber, means for controlling the supply of oil to said pipe, and pipes having their upper ends secured in the bottom of said chamber and projecting above said bottom to distances proportionate to the quantities of oil desired to pass through the several pipes.

In testimony that I claim the foregoing as my own I have hereto affixed my signature in the presence of two witnesses.

GOTTLEIB SCHNEIDER.
